DIAGNOSTIC UNIT FOR ANALYZING LEUKEMIA

Guido Vicario, Piazzale Giulio Cesare 14, Milan, Italy

Filed Apr. 4, 1968, Ser. No. 11,300

Term of patent 14 years

Int. Cl. D24—02

U.S. Cl. D83—1

FIG. 1 is a front view of the diagnostic unit for analyzing leukemia.

FIG. 2 is a plan view of the diagnostic unit for analyzing leukemia showing an articulated small shaft for linkage to the microscope (not shown).

FIG. 3 is a side view.

FIG. 4 is a sectional view of a detail of an elongated seat for a finger pushbutton.

FIG. 5 is a bottom view.

FIG. 6 is a side view, showing the opposite side from that shown in FIG. 3.

The undisclosed rear is substantially plane and unornamented.

I claim:

The ornamental design for a diagnostic unit for analyzing leukemia, as described.
